UNITED STATES PATENT OFFICE.

EDUARD VON KILANYI, OF BUDA-PESTH, AUSTRIA-HUNGARY.

APPARATUS FOR DISPLAYING TABLEAUX VIVANT.

SPECIFICATION forming part of Letters Patent No. 528,373, dated October 30, 1894.

Application filed April 19, 1894. Serial No. 508,143. (No model.)

To all whom it may concern:

Be it known that I, EDUARD VON KILANYI, a subject of the Emperor of Austria-Hungary, and a resident of Buda-Pesth, Austria-Hungary, have invented certain new and useful Improvements in Apparatus for Displaying Tableaux Vivant, of which the following is a specification.

My invention relates to apparatus for displaying living pictures and is an improvement on that filed by me March 29, 1894, Serial No. 505,625.

In the accompanying drawings which embody my invention Figure 1 is a vertical section of the device. Fig. 2 is a side view of same. Fig. 3 is a top plan view of same. Fig. 4 is a top plan view of the lower supporting frame; Fig. 5, an end view, and Fig. 6 a plan view of the upper table and scenic sections, without the central track and moved in a straightline back and forth on the stage track.

Referring more particularly to the drawings, it will be noted that I have substituted for the lower table in the application above referred to a frame A, consisting of pieces suitably bolted or joined together so as to be readily assembled or taken apart and provided with wheels or rollers a' journaled in said frame at suitable intervals apart, said 30 rollers moving upon a detachable track a laid upon the floor of the stage.

The frame A, movable as described, has secured to it a transverse track b, upon which moves a second supporting frame or table B, 35 provided with wheels or rollers b', moving upon said track. This table has secured to it on its top a circular track C upon which move the wheels d' of the scene supporting table D. This latter table consists of sections 40 (preferably four or more), each independent of the other but suitably joined together, as will be hereinafter explained. The sections are of box form to give strength and in addition to provide a tank or tanks G for water effects. The four sections as here shown 45 (Fig. 3) are joined together by a four arm cross plate H bolted to the under side of the sections as shown at i, and at the center is

a central pintle p passing down through table B.

Upon the upper surface of table D upon each independent section are secured stays e, against which rest the scenic back grounds E. These stays are removably attached to the table. The scenic back grounds are hinged 55 together so as to be readily and quickly detached and folded up. This construction enables me to place the apparatus in its desired position on the stage easily and quickly, and having arrived at the proper position 60 at the rear and near to the frame F has a reciprocal motion and a motion of translation relative to said frame, that is to say, the front of each section must be very near the edge of the frame so as to hide the table sections and make the illusions complete. However, to do this quickly and noiselessly the table must be run back so as to clear the edges of the frame, and this is done by moving it 65 back and forth on track b by means of a suitable lever, or in any other mechanical way. Having drawn the table back on its track until arrested by the stops b² at the ends of track b, these stops being placed at a distance just enough to clear the edge of the picture frame 70 and permit the table to be revolved, hence it is shown that the table D has a combined motion of translation and rotation.

The picture frame F has an interior mat f, about which is arranged a series of lights g, 80 which light up by reflection the back ground E with the posed figures.

The track C is preferably hinged as shown at c, so as to be readily folded for transportation, and the several parts of the table or 85 frame B are secured together by bolt plates k.

In operation, the track a is laid upon the floor of the stage and the apparatus moved up to the frame F provided with legs let into the stage floor.

The scenic effects E for the first two, three or four pictures are placed in position against the stays e, and the figurants for the first two or three pictures are posed in their respective sections on table D. After picture 95 No. 1 is shown, the table is moved backward,

then revolved to bring into view picture No. 2. Then the back ground E of No. 1 is removed and back ground of picture 5 with its figurants substituted. This motion of translation and rotation is continued until all the pictures have been displayed and the apparatus is then moved back on its track, the track removed, and the stage is clear for any other part of the play.

10 In some theaters the stage may be too narrow to revolve the scene table, and in this instance the circular track may be dispensed with and the scene sections be arranged in a straight line and moved back and forth on the lower frame A or stage track a. The back grounds will be removably arranged and the operation of setting and remounting the pictures will be the same as before described.

15 Having thus described my invention, what I claim as new, and desire to secure by Letters Patent, is—

1. In an apparatus of the nature described,

a movable platform in combination with a table supported by and movable thereon, and a scene supporting table divided into independent sections and rotatable on said table. 25

2. The combination with the movable frame A of the table B moved laterally thereon, and a sectional table D rotating on table B, said table D having one or more water compartments. 30

3. The combination with the laterally moving frame A and table B of a table D pivotally mounted and rotatable on table B, said table D having removable back grounds E and supports e. 35

Signed at New York, in the county of New York and State of New York, this 16th day of April, A. D. 1894.

EDUARD VON KILANYI.
